UNITED STATES PATENT OFFICE.

SAMUEL J. KINGSTON, OF BRIDGEWATER, MASSACHUSETTS.

DESIGN FOR A SNAP-HOOK.

SPECIFICATION forming part of Design No. 25,798, dated July 21, 1896.

Application filed May 9, 1896. Serial No. 590,948. Term of patent 3½ years.

To all whom it may concern:

Be it known that I, SAMUEL J. KINGSTON, of Bridgewater, in the county of Plymouth and State of Massachusetts, have invented and produced a certain new and original Design for Snap-Hooks, of which the following is a specification, reference being had to the accompanying drawing, forming a part thereof.

My new design for a snap-hook is intended particularly for connecting the ends of straps, such as driving-reins, said snap-hook comprising two complementary members of similar shape. Therefore I illustrate both of said members in the accompanying drawing, in which the figure represents a perspective view of the two parts of the hook connected together.

The leading feature of my design consists in the bifurcated base-plate, having a gradually-narrowing projection from the edge thereof. In the drawing the two members

of the snap-hook are indicated at *a* and *a'*, each of said members having its base bifurcated to form two parallel rectangular plates 25 1 1, connected at one edge by the web 2. From the web 2 a projection 3 extends in a plane continuous with that of the base, said projection having its sides and edges inclined or narrowed for a short distance, and then 30 extended forward, as at 4, with parallel sides and edges.

I claim—

The design for a snap-hook, substantially as shown and described.

In testimony whereof I have signed my name to this specification, in the presence of two subscribing witnesses, this 4th day of January, A. D. 1896.

SAML. J. KINGSTON.
